(57) **CLAIM**

I claim the ornamental design for the device mounting apparatus, as shown and described.

DESCRIPTION

FIG. 1 is an isometric view of a device mounting apparatus of the present invention;

FIG. 2 is a direct front view thereof;

FIG. 3 is a direct top-down view thereof;

FIG. 4 is a right side view, the left side view is a mirror image thereof; and,

FIG. 5 is an isometric view of thereof, attached to a flat screen monitor and holding a device.

It is noted both the monitor and device are depicted as dashed lines to clearly disavow any claim to the ornamental design of the dashed elements.

The bottom of the device mounting apparatus is flat and devoid of ornamental features as such the bottom view forms no part of the claimed design. The device mounting apparatus is shown in its environment in FIG. 5, broken lines are used to indicate that elements of the environment form no part of the claimed design.

The broken line shown in FIG. 5 forms no part of the claimed design.
